UNITED STATES PATENT OFFICE

128,057

DESIGN FOR A PORTABLE GRANDSTAND FRAME

John F. Roney and Richard W. Page, Hollywood,
Cal., assignors to Safway Steel Scaffolds Co. of Wisconsin, Wauwatosa, Wis., a corporation of Wisconsin

Application March 18, 1940, Serial No. 91,031

Term of patent 7 years

To all whom it may concern:

Be it known that we, John F. Roney and Richard W. Page, citizens of the United States of America and residents of Hollywood, in the county of Los Angeles and State of California, have invented a new, original, and ornamental Design for a Portable Grandstand Frame, of which the following is a specification, reference being had to the accompanying drawing, forming a part thereof.

In the drawing:

The single figure shows a perspective view of the portable grandstand frame showing our new design.

We claim:

The ornamental design for a portable grandstand frame, as shown.

JOHN F. RONEY.
